UNITED STATES PATENT OFFICE.

ALFRED H. BENJAMIN, OF EAST ORANGE, NEW JERSEY, ASSIGNOR TO BENJAMIN & JOH OF NEWARK, NEW JERSEY, A FIRM.

APPAREL-CORSET.

No. 873,489.

Specification of Letters Patent. Patented Dec. 10, 1907.

Application filed March 9, 1907. Serial No. 361,473.

To all whom it may concern:

Be it known that I, ALFRED H. BENJAMIN, a citizen of the United States, residing at East Orange, in the county of Essex and State of New Jersey, have invented an Improvement in Apparel-Corsets, of which the following is a specification.

My invention relates to improvements in apparel corsets of the closed back and laced and hooked front style and form, with the object of applying tension in the corset below the waist for the reduction of an over-full figure and the production of an abdominal support and a flat front effect for the corset.

15 In the corset of my invention substantially the upper half of the corset at the back is closed while substantially the lower half of the corset is open and provided with lacing edges and by preference these respective constructions overlap for an appreciable distance at about the center of the corset or waist line. At the front I provide abdominal flaps

20 secured to the under side of the corset and meeting at the center where steels and hook fasteners are employed for connecting the flaps together. This line of union comes beneath the center of the lacing front adjacent and parallel to which are the front steels and hook fasteners.

25 Referring particularly to Figs. 1 and 2, which show the preferred form of my invention at the front of the corset, $e e^1$ represent the front lacing edges which extend from the top edge of the corset down to the point e^2 . They are provided with eyelets 5 and with a lace or cord 6, the tying point of the said lace or cord being adjacent to or slightly below the point e^2 where the separated members $e e^1$ join. From the point e^2 the front portions of the corset are permanently and firmly connected at a center sewed line of union f . I have shown and prefer to employ a back strip or anchor member f^1 of fabric (see Fig. 2) which extends across this central sewed line of union f from the point e^2 downward and through the said fabric portions I prefer to place eyelets 7. This anchor more firmly connects the fabric of the corset front with the fabric of the back strip f^1 and said transverse strip f^1 overcomes any tendency of the front portion of the corset to separate along the line of sewing f , and I have shown (Figs. 2, 5 and 6) and prefer to employ a vertical back strip of tape or substantial material f^2 sewed to the fabric body of the corset and strengthening the sewed line of union along the sewed line of union f . Adjacent to the front lacing edges $e e^1$ are the front steels $h h^1$. These are parallel with one another and substantially parallel with the

30 balance of the distance from this point to the lower edge. This construction fixes the corset at the front and provides for the application of a tension below the waist by the lacing at the back, which lacing may be taken in to any desired extent, the same only affecting the lower half of the corset. The lacing at the front from the waist up to the upper edge of the corset provides for tension or more often for looseness and comfort in fitting the bosom, the effect of which is to increase or enhance the flat front of the corset.

35 In the drawing, Figure 1 is an elevation at the front of the corset and the center thereof, Fig. 2 is a rearward elevation of the same parts at the same time showing the abdominal flaps, a portion of which is broken away at the upper edge to show a strengthening strip. Fig. 3 is an elevation at the back and central portion of the corset. Fig. 4 is a sec-

40 tional plan at the dotted line $x x$, of Fig. 3. Fig. 5 is a sectional plan at the dotted line $y y$, of Fig. 1. Fig. 6 is a sectional plan at the dotted line $z z$, of Fig. 1, which section extends through the strengthening strip shown in Fig. 2 and the eyelets thereof, and Fig. 7 is an elevation at the central front portion of the corset showing a form of my invention and in which a portion is broken away to more clearly illustrate the abdominal flaps.

45 $a b$ are the half portions of the corset and c the solid back portion which extends from the upper edge of the corset down and preferably past the waist line to the line c^1 (see Fig. 3), and referring to this figure $d d^1$ represent the lacing edges which extend from the lower edge of the corset up past the lower end c^1 of the solid back c to the upper ends 4. The same are provided with eyelets 2 and a lace or cord 3 and the solid back and lacing edge appreciably overlap.

50 Referring particularly to Figs. 1 and 2, which show the preferred form of my invention at the front of the corset, $e e^1$ represent the front lacing edges which extend from the top edge of the corset down to the point e^2 . They are provided with eyelets 5 and with a lace or cord 6, the tying point of the said lace or cord being adjacent to or slightly below the point e^2 where the separated members $e e^1$ join. From the point e^2 the front portions of the corset are permanently and firmly connected at a center sewed line of union f . I have shown and prefer to employ a back strip or anchor member f^1 of fabric (see Fig. 2) which extends across this central sewed line of union f from the point e^2 downward and through the said fabric portions I prefer to place eyelets 7. This anchor more firmly connects the fabric of the corset front with the fabric of the back strip f^1 and said transverse strip f^1 overcomes any tendency of the front portion of the corset to separate along the line of sewing f , and I have shown (Figs. 2, 5 and 6) and prefer to employ a vertical back strip of tape or substantial material f^2 sewed to the fabric body of the corset and strengthening the sewed line of union along the sewed line of union f . Adjacent to the front lacing edges $e e^1$ are the front steels $h h^1$. These are parallel with one another and substantially parallel with the

lacing edges and they are provided with hook devices of ordinary and well known form.

On the front portion of the corset on the 5 under side and below the point e^2 I employ the abdominal flaps i^1 i^2 . These are shown clearly in Figs. 2 and 7; they are secured to the fabric body along the opposite lines of sewed union 9 10 and their meeting edges 10 are provided with hook devices 11. This central line coincides with the central sewed line of union f .

In the form of my invention shown in Fig. 7, the lacing edges k l at the front of the corset 15 extend all the way from the top edge to the bottom edge with eyelets 12 and cords or laces 13, and in this form of my invention the front steels m n are employed and they are adjacent to and substantially parallel with 20 the lacing edges k l , said front steels having hook devices 14; therefore the only difference between this form of my invention and that shown in Fig. 1, is the fact that in the form Fig. 7, the lacing is continued through 25 out the corset between the top and bottom edges instead of from the upper edge to a point of closing. I however prefer the form shown in Fig. 1.

In the use of this corset it is to be removed 30 from the person by opening the front steels. This is a fact either with reference to the device of Fig. 1 or Fig. 7, and when the corset is adjusted to the figure the abdominal flaps are first hooked and then the steels h h^1 35 brought together and hooked, because the corset is so made especially with reference to the device Figs. 1 and 2, that when the abdominal flaps are hooked under tension and the body of the corset also hooked the 40 point e^2 down is also under tension. The tension applied below the waist to the corset of my improvement is effected at the laced edges d d^1 at the back by tightening the lace or cord 3 thereof to any desired extent, and 45 while it is desirable that the upper portion of these laced edges d d^1 from the point e^1 of the solid back up to the upper edges 4 should have only sufficient tension to lie smoothly over the solid back, the laced edges lower 50 down toward the lower edge of the corset may be brought nearer together under tension or spread further apart with greater freedom as may be desired or found comfortable to the wearer of the corset, it being 55 apparent that the nearer these edges are brought together under tension, the tighter will be the corset below the waist and the more the same will hold in the figure.

The lacing front from the point e^2 to the 60 upper edge of the corset provides for an adjustment of the upper portion of the corset—above and independent of any tension applied below the waist to the abdominal flaps and lower part of the corset—to fit the 65 bosom in providing comfort to the wearer

and a necessary fullness therefor as well as a graceful figure.

I have shown in Figs. 2 and 7, and prefer to construct the abdominal flaps with substantially parallel vertically disposed bone 70 pockets and bones for the purpose of stiffening the same.

I claim as my invention:

1. In a corset and in combination with the half portions thereof, a solid back central portion from slightly below the waist to the top edge of the corset and lacing edges also at the center of the back from above the waist line to the lower edge, whereby the lower portion of the solid back and the upper laced edges 80 overlap at the waist for a support to the waist.

2. In a corset and in combination with the half portions thereof, front lacing edges that extend centrally from the upper edge of the corset to slightly below the waist line, with 85 the front of the corset below this point made solid, front steels parallel with and adjacent to the laced edges at one side of the center of the corset and extending from the top to the bottom of the corset, and a transverse back 90 or anchor strip on the under side of the corset at the front and connected directly below the point of separation of the front into the lacing edges for the purpose of strengthening the beginning of the sewed line of union.

95

3. In a corset and in combination with the half portions thereof, front lacing edges that extend centrally from the upper edge of the corset to slightly below the waist line, with 100 the front of the corset below this point made solid, front steels parallel with and adjacent to the laced edges at one side of the center of the corset and extending from the top to the bottom of the corset and abdominal flaps beneath the corset portions at the front and 105 sewed permanently at its edges to the halves of the corset with the meeting hooked edges of the abdominal flaps at the center of the corset below the central sewed line of union.

4. In a corset and in combination with the half portions thereof, front lacing edges that extend centrally from the upper edge of the corset to slightly below the waist line, with 110 the front of the corset below this point made solid, front steels parallel with and adjacent to the laced edges at one side of the center of the corset and extending from the top to the bottom of the corset and abdominal flaps formed of fabric members with series of substantially vertical bones in pockets and secured at the sewed lines of union 9 10 to the under surfaces of the corset portions at the front and with hook devices connecting the abdominal flaps at the center of the corset 115 below the central sewed line of union.

120

5. In a corset and in combination with the half portions thereof, front lacing edges that extend centrally from the upper edge of the corset to slightly below the waist line, with 125 the front of the corset below this point made

130

solid, front steels parallel with and adjacent to the laced edges at one side of the center of the corset and extending from the top to the bottom of the corset, a transverse back or anchor strip on the under side of the corset at the front and connected directly below the point of separation of the front into the lacing edges for the purpose of strengthening the beginning of the sewed line of union and 10 abdominal flaps formed of fabric members with substantially vertical bones in pockets secured at the sewed lines of union 9 10 to the under surfaces of the corset portions at the front and with hook devices connecting the 15 abdominal flaps at the center of the corset below the central sewed line of union.

6. In a corset and in combination with the half portions thereof, front lacing edges that extend centrally from the upper edge of the 20 corset to slightly below the waist line, with the front of the corset below this point made solid, front steels parallel with and adjacent to the laced edges at one side of the center of the corset and extending from the top to the 25 bottom of the corset, and the back of the corset at the center thereof formed solid from the upper edge to a point below the waist line, and lacing edges from above the waist line to the lower edge of the corset for applying 30 tension to the corset below the waist, whereby the corset at the front is adjustable above the waist and at the back below the waist.

7. In a corset and in combination with the half portions thereof, front lacing edges that 35 extend centrally from the upper edge of the corset to slightly below the waist line, with the front of the corset below this point made solid, front steels parallel with and adjacent to the laced edges at one side of the center of the corset and extending from the top to the bottom of the corset, a transverse back or anchor strip on the under side of the corset at the front and connected directly 40 below the point of separation of the front into the lacing edges for the purpose of strengthening the beginning of the sewed line of union, and the back of the corset at the center thereof formed solid from the upper edge to a point about the waist line, and 45

lacing edges from about the waist line to the 50 lower edge of the corset for applying tension to the corset below the waist.

8. In a corset and in combination with the halves thereof and the front steels and their fasteners at one side of the center of the corset at the front, of the central lacing edges at the front extending from the top of the corset to about or slightly below the waist line and with a solid sewed line of union from this point down to the lower edge of the corset, 55 a transverse strip secured to the under surface or back of the corset at and below the termination of the laced edges and over the beginning of the sewed line of union, which strip is sewed to the corset, and eyelets 60 placed through the corset and through the said strip at either side of the center, forming the lower or terminal eyelets for the front lacing so that the lacing assists in the function of the said strip in anchoring or supporting 70 the front of the corset where the sewed line of union begins.

9. In a corset and in combination with the halves thereof and the front steels and their fasteners at one side of the center of the corset at the front, of the central lacing edges at the front extending from the top of the corset to about or slightly below the waist line and with a solid sewed line of union from this point down to the lower edge of the corset, a 75 transverse strip secured to one surface of the corset at and below the termination of the laced edges and over the beginning of the sewed line of union, which strip is sewed to the corset, and eyelets placed through the 80 corset and through the said strip at either side of the center, forming the lower or terminal eyelets for the front lacing so that the lacing assists in the function of the said strip in anchoring or supporting the front of the 85 corset where the sewed line of union begins. 90

Signed by me this 11th day of February 1907.

ALFRED H. BENJAMIN.
